UNITED STATES PATENT OFFICE.

JOHN MCKENNEY, OF ANACONDA, MONTANA.

AUTOMATIC REVERSIBLE MOTOR.

1,081,458.

Specification of Letters Patent. Patented Dec. 16, 1913.

Application filed July 7, 1913. Serial No. 777,699.

To all whom it may concern:

Be it known that I, JOHN MCKENNEY, of Anaconda, in the county of Deerlodge and State of Montana, have invented certain new 5 and useful Improvements in Automatic Reversible Motors; and I hereby declare that the following is a full, clear, and exact description thereof, reference being had to the accompanying drawings, which form 10 part of this specification.

This invention is an improvement in rotary engines and motors and has particular reference to means for automatically reversing the engine after a predetermined number 15 of revolutions of the main shaft thereof in either direction.

The invention provides a novel valve controlling mechanism by which the direction of rotation of the main engine shaft is controlled, and an engine equipped therewith is especially adaptable for driving reciprocating parts of machines; such as planer beds, and other devices. I also provide means whereby the valve controlling mechanism 25 can be rendered inactive and allow the engine to run continuously in either direction desired by the operator.

In the accompanying drawings I have illustrated a practical form of motor and 30 valve reversing mechanism embodying the invention and will describe same with reference thereto.

In said drawings—Figure 1 is a sectional elevation of a motor showing the working 35 chambers, pistons and ports, and valve chamber. Fig. 2 is an exterior view showing the valve mechanism. Fig. 3 is a similar view showing the parts in different position. Fig. 4 is a detail edge view of Fig. 2.

The engine casing 1 may be of any suitable form and contains a working chamber 1^a within which is eccentrically located a rotary piston 2 which is mounted on a shaft 2^b. The piston is provided with four equi-distant radial slots 2^c in which slots are slidably mounted abutments 3; and the diametrically opposite abutments 3 are connected by rods 3^a which extend diametrically through the piston, the connected abutments 50 being so formed that the abutments will move in and out according to the curvature of the outer wall of the chamber 1^a and will always maintain practically a fixed relation to each other.

55 At the point where the piston 2 contacts

with the outer wall of the chamber 1^a I preferably locate a packing 3^c which will prevent short circuiting of fluid from one side of this packing to the other.

Communicating with the chamber 1^a at 60 opposite sides of the packing 3^c are ports 4^a, 4^b which also communicate with a valve chamber 4, in which chamber is mounted a slideable valve 5 which is adapted to establish communication between either ports 4^a or 4^b 65 and the main outlet port 4^c, according to the position of the valve 5. When valve 5 establishes communication between ports 4^a, (or 4^b), and port 4^c it opens communication between the other ports 4^b, (or 4^a), and the 70 chamber 4. Fluid, such as steam, compressed air or water under pressure, is admitted into the chamber 4 and will flow for example through port 4^b into chamber 1^a and engage abutments 3 therein and force 75 piston 2 to rotate through cylinder to the left until fluid can escape through port 4^a to outlet 4^c. If the valve be shifted to the right fluid will pass from chamber 4 through port 4^a to the chamber 1^a and port 4^b and 80 then to the outlet 4^c and the piston will rotate to the left.

The valve 5 as shown is provided with a rack 5^a meshing with a segment 6^a on a shaft 6 which extends outside the valve chamber 85 and is provided with operating arm 6^b; to this arm 6^b may be connected a stud 6^c to which is pivotally connected the upper end of an actuating spring 9 hereinafter referred to. The arm 6^b may also have a stud 90 6^d on its inner side which is adapted to engage with a catch 7^d on the lever 7 when the arm is swung to the left, or with catch 7^e when the arm is swung to the right. The lever 7 is pivoted to the frame as at 7^a and 95 is provided with a cam portion 7^c adapted to be alternately engaged by tripping pins 8^a on a gear 8 as hereinafter explained, and cause lever 7 to release the pin 6^d.

The gear 8 is rotatably mounted on a stud 100 8^c attached to the side of the frame and it meshes with a pinion 10 rotatably mounted on a stud 10^a attached to the frame, and this pinion 10 is fast to a gear 10^b also rotatably mounted on stud 10^a; and gear 10^b meshes 105 with a pinion 2^c on the shaft 2^b.

To the projecting end of the stud 10^a may be fixedly attached the lower end of the spring 9, which is preferably a leaf spring and its upper end is engaged with the stud 110

6^c on the arm 6^b. The studs 8^a are detachably attached to the gear 8 in any suitable manner. To the gear 8 is attached a stud 8^b preferably in radial alinement with the axis 5 of the gear and between the pins 8^a. This stud 8^b is adapted to engage with the spring 9 and deflect the latter to right or left, according to the direction of rotation of gear 8.

Assuming that the main pinion is rotating 10 clock-wise in the position shown in Fig. 2, and the stud 6^a of the arm 6^b is then engaged and locked by the catch 7^d, (the gearing being so proportioned that the main piston will make a number of revolutions 15 to each revolution of the gear 8, for example say 10), as the gear 8 rotates the stud 8^b engages the spring 9 and begins to deflect it to the right and continues to deflect it until pin 8^a comes into engagement with and 20 raises lever 7 sufficiently to cause catch 7^d to release the stud 6^a; as soon as the stud is disengaged spring 9 (which is then flexed) immediately swings arm 6^b to the right and brings the stud 6^a into engagement 25 with catch 7^e on lever 7. This movement of the arm oscillates shaft 6 and through segment 6^a slides the valve 5 to the right, cutting off communication between the chamber 4 and port 4^b and establishing communication 30 between said chamber and port 4^a; and between port 4^b and the discharge port 4^c. This produces a reversal of movement of the main piston; and this reverse movement continues until in the reverse rotation 35 of gear 8 the other stud 8^b engages spring 9 and moves it to the left, the flexure of the spring increasing until pin 8^a engages cam 7^c and causes catch 7^d to release pin 6^a, whereupon spring 9 throws the arm 6^b 40 back to the left, thereby shifting the valve to its first position and causing the piston to turn in the opposite direction. By this means the valve is automatically shifted and the shift of the valve is effected quickly. 45 The number of rotations of the main piston in the intervals between each shift of the valve is determinable by proportioning the gears, and by the relative position of pin 8^a. If it is desired to have the engine run 50 for any length of time in one direction only, the stud 8^b can be removed and the valve will then remain in either position to which it is shifted by the operator.

What I claim is:

55 1. In combination, an engine, and a valve adapted to control the engine; with a rock shaft and connections for operating the valve, a lever on said rock shaft, a spring connected with said lever adapted to throw 60 it in either position, a rotary member adapted to engage the spring and flex same until it causes the shift of the valve; gearing for actuating said member, a catch for holding the valve locked in

either position, and means on said rotary member for disengaging the catch.

2. In combination, an engine, and a valve for controlling the engine; with a rock shaft and connections for actuating said valve, and a lever on said rock shaft; with 70 a rotary member beside said lever, gearing for operating said rotary member from the main engine shaft, a spring beside said member connected with said lever, and a stud on said member adapted to engage and flex 75 said spring until the latter throws the lever and shifts the valve.

3. In combination, an engine, a valve for controlling the inlet of fluid to the engine, a rock shaft and connections for actuating 80 said valve, and a lever on said rock shaft; with a rotary member beside said lever, gearing for operating said rotary member from the main engine shaft, a spring beside said member connected with said lever, a 85 stud on said member adapted to engage and flex said spring until the latter throws the lever and shifts the valve; a catch for locking the lever to hold the valve in either extreme position, and means on said rotary 90 member adapted to release the catch to permit the spring to shift the lever.

4. In combination with an engine, and a valve adapted to control the inlet of fluid to the engine; a rock-shaft and connections 95 for operating the valve; a lever on said rock-shaft, a device connected with said lever and adapted to throw said lever in either position, a gear adjacent said device, gearing for actuating said gear, and a stud 100 on said gear adapted to engage said device alternately on opposite sides and cause it to shift the valve.

5. In combination with an engine, a valve chamber, and a valve in said chamber, a 105 rock-shaft and connections for operating the valve, a lever on said rock-shaft, a flat-spring engaging said lever and adapted to throw it in either position, and a rotary member adjacent said means adapted to engage 110 said spring alternately on opposite sides to cause it to shift the valve, and gearing for actuating said member, substantially as described.

6. In combination, an engine, and a valve 115 adapted to control the inlet and outlet of fluid to the engine; a rock-shaft and connections for operating the valve, and a lever on said rock-shaft; with a device adapted to throw said lever in either position, a rotary 120 member adapted to engage said device alternately on opposite sides and cause it to shift the valve; a catch for holding the valve locked in either position, and means on said rotary member for disengaging the catch to 125 allow the device to shift the valve.

7. In combination with an engine, and its main valve, a rock-shaft and connections for

operating the valve, a lever on said rock-
shaft, a spring connected with said lever
adapted to throw said lever in either posi-
tion, a rotary member adapted to engage
5 the spring alternately on opposite sides and
flex same until it causes a snap shift of the
valve, and gearing for actuating said mem-
ber.

In testimony that I claim the foregoing
as my own, I affix my signature in presence
of two witnesses.

JOHN McKENNEY.
